(57) **CLAIM**

The ornamental design for a hubcap for a wheel, as shown and described.

DESCRIPTION

Figure 1.1 is a front view of a hubcap for a wheel showing our new design;

Figure 1.2 is a back view thereof;

Figure 1.3 is a left side view thereof;

Figure 1.4 is a right side view thereof;

Figure 1.5 is a top view thereof;

Figure 1.6 is a bottom view thereof; and

Figure 1.7 is a perspective view thereof.

(Continued)

The portion of the design shown in the color Light Blue is for the purpose of illustrating portions of the claimed design that forms no part of the claimed design.

1 Claim, 7 Drawing Sheets
